UNITED STATES PATENT OFFICE.

ALEXANDER N. PIERMAN, OF NEWARK, NEW JERSEY.

TOY AND GAME.

1,032,501.

Specification of Letters Patent. Patented July 16, 1912.

Application filed May 4, 1912. Serial No. 695,045.

To all whom it may concern:

Be it known that I, ALEXANDER N. PIERMAN, a resident of Newark, county of Essex, State of New Jersey, and a citizen of the United States, have invented a certain new and useful Improvement in Toys and Games, of which the following is a specification.

My invention relates to apparatus used for the purpose of playing games of chance.

10 Among its objects are the provision of an apparatus whereby the human element or the personal equation of the player is substantially eliminated, so that the results produced are dependent entirely upon chance 15 alone, and are unaffected by the manner in which the device is manipulated by the individual player.

Other objects of the invention are the provision of an apparatus of the kind referred 20 to, which shall be simple, neat and inexpensive to manufacture, and which shall be durable and not easily injured, and the operation of which will be simple and readily understood by the players.

25 With the foregoing and related objects in view, my invention consists in the parts, improvements and combinations hereinafter set forth and claimed.

While I have shown and shall describe one 30 specific embodiment of my invention, it is to be understood that the same is for the purpose of illustration merely, and that my invention is not confined thereto, but is as broad as my claims.

35 In the drawings forming a part of the specification Figure 1 is a central, cross-sectional view of one form of game apparatus embodying my invention, and Fig. 2 is a plan view of the apparatus shown in Fig. 1.

40 The reference numeral 1 indicates the base of the apparatus, which in the form shown consists in a block of wood or similar material, though it is to be understood that it may have any form and be made of any ma-

45 terial suitable for the purpose. The upper portion of member 1 is dished or concaved as shown at 2 and is provided immediately adjacent to its dish shaped border with a plurality of recesses or pockets 3, 3 separated

50 from one another and preferably arranged in an annular row. In the form shown the member 1 is provided with a central recess or opening 4. A diaphragm 5 is secured to the member 1 as by screws 6 and covers or

55 closes the recess or opening 4. This diaphragm is bowed or bulged in the same

manner as the bottom of an ordinary oil can, it being shown in the drawing in full lines as bowed or bulged downwardly, and in dotted lines as bowed or bulged upwardly. 60 A pocket 7 or other receiving means is provided on the diaphragm 5 to receive a movable object, such as the ball 8, with which games may be played. When the diaphragm 5 is pushed upward beyond its intermediate 65 position, it will immediately spring to its limit in the upward direction, thus throwing the ball 8 to a moderate height; the ball falling upon the upper convex surface of the diaphragm 5 or on some other point of 70 the base member 1, will ultimately be deposited in one of the recesses or pockets 3.

For the purpose of the convenient operation of the diaphragm 5 to cause it to throw the ball 8 upward, I preferably provide a lever 9 fitting in a recess 10 in the base member 1 and pivoted thereto at 11. A finger button 12 is provided at the outer end of the lever 9 and the opposite end is formed with a knob or head 13 immediately beneath the 80 center of diaphragm 5 and the pocket 7. A stop 14 is provided to limit the downward movement of the lever 9 upon application of pressure to the finger button 12. While I have illustrated this lever arrangement for 85 the purpose of actuating the diaphragm so as to make it pass the middle point and throw the ball upward, it will be understood that my invention is not limited thereto but that other means may be resorted to for imparting an initial upward movement to the diaphragm 5.

A guard is preferably provided around the outer edge of the apparatus for preventing the balls in play from jumping out. As 95 shown, this guard consists of an annular ring 15, preferably of metal, having an inwardly extending lip 16, thus making it serve as an effectual guard for preventing the ball in play from going beyond proper 100 bounds.

Characters indicating the value of the recesses or pockets 3 in the game, are placed in or adjacent to the said recesses or pockets. In the form of device which I have selected 105 for illustration, the value of the separate pockets is indicated by numerals placed therein. In the form shown, 16 such pockets are provided and the numerals indicating their value in the game have been arranged 110 so that the sum of adjacent numerals should be as large in number as possible, the nu-

merals being arranged for this purpose by numbering alternate pockets or recesses in sequence in a clock-wise order, beginning with the numeral 1 and continuing until the 5 numeral 8 is reached. Then the numeral 9 is placed between 8 and 1, and the higher numerals up to 16 are arranged alternately in anti-clockwise direction. With this arrangement the sum of adjacent numerals— 10 except for the 9 or 1—is either 17 or 18. Other arrangements may be resorted to and other characters may of course be chosen for the purpose of designating the value of the various pockets, the arrangement which I 15 have described above being chosen for the purpose of adding to the interest of the game, making it possible for a subsequent player to displace the ball deposited by a prior player and to drive it into an adjacent 20 pocket which may be of a value greatly different from that in which it was originally deposited, thus greatly increasing the element of chance in the playing of games with the apparatus.

25 An apparatus constructed in accordance with my invention may be used for playing a variety of games according to the directions which may be given by the manufacturers, or the choice of the individual player.

30 One way in which the game may be played therewith is the following: A number of balls 8, preferably of different colors, may be provided and each player may be given 35 balls of one color. The players may then place the balls given them in turn in the pocket 7, and by pressure on the button 12 put the ball in play by imparting an initial upward thrust to the diaphragm 5, and the diaphragm, being pushed in this way beyond the middle position, will bow upward 40 suddenly and throw the balls in the pocket upward, whereupon it will fall backward upon the upwardly bowed surface of the diaphragm 5 or elsewhere within the bounds 45 of the base member 1; and will ultimately come to rest in one of the pockets 3. The next player places the ball of the color given him in the pocket 7, either first pushing the diaphragm 5 downward, or pushing it 50 downward at the same time or after the ball is placed therein, and this player may in turn depress the button 12 placing the ball of his color in play, and after it has been thrown upward it will come to rest 55 in one of the pockets with or without having displaced any balls already played from the pockets in which they have been deposited, to other pockets. This sequence may be continued until all the balls are 60 played and the score may be computed by adding up the totals of the numbers of pockets or recesses in which the balls of the colors chosen by the different players have been deposited, or in various other manners 65 as rules may be established for the compu-

tation of scores. As already stated, however, the playing of the game as outlined above is merely illustrative, and a variety of games may be played with the apparatus which has been illustrated.

Having now described my invention I claim:

1. In an apparatus of the class described, a member provided with a plurality of recesses or pockets, a buckled spring member 70 and means for moving said buckled spring member past the middle position allowing it to spring to the opposite buckled position, substantially as set forth.

2. In an apparatus of the class described, 80 the combination of a member provided with a plurality of recesses or pockets, spring means for imparting movement to an object, and hand operated means for setting said spring means into action, substantially as 85 set forth.

3. In an apparatus of the class described, a member provided with a plurality of recesses or pockets, a buckled diaphragm provided with means for receiving a movable 90 object, and hand operated means for moving said diaphragm past the middle position leaving it free to spring to its opposite extreme position, substantially as set forth.

4. In a device of the class described, the 95 combination of a member provided with a plurality of recesses or pockets, a buckled diaphragm centrally arranged in said member, and provided with means for receiving a movable object, and means for imparting 100 a thrust to said diaphragm, substantially as set forth.

5. In a device of the class described, the 105 combination of a substantially dish shaped member provided with a plurality of recesses or pockets arranged in an annular row, a buckled diaphragm arranged centrally of said member, and provided with means for receiving a movable object at substantially the center thereof and means 110 for imparting a thrust to said buckled diaphragm, substantially as set forth.

6. In a device of the class described, a substantially dish shaped base member provided with a central opening and with an 115 annular row of recesses or pockets, a buckled diaphragm secured to said member and closing the opening in the center and provided with means for receiving a movable object, and means extending beyond the side of the 120 base member for imparting a thrust to the diaphragm, substantially as set forth.

7. In a device of the class described, a substantially dish shaped member, provided with a plurality of recesses or pockets, a 125 retaining overhanging ring around the periphery of said member, a buckled diaphragm centrally arranged in said member and provided with means for receiving a movable object, and a lever pivoted in said 130

member for imparting an initial thrust to said diaphragm, substantially as set forth.

8: In a device of the class described, a substantially dish shaped member provided
5 with a central opening and an annular row
of recesses or pockets arranged around said
opening and having a retaining ring or wall
arranged around and above the periphery
thereof, a buckled diaphragm secured to
10 said member and closing the central opening
therein, a lever pivoted in the said member
and extending beyond the same and pro-

vided with a finger piece, the said member terminating at its opposite end at or near the center of the diaphragm, and a stop for 15 limiting the movement of said lever, substantially as set forth.

This specification signed and witnessed
this 2nd day of May, 1912.

ALEXANDER N. PIERMAN.
